UNITED STATES PATENT OFFICE.

MAX M. KOCH, OF CLEVELAND, OHIO.

OVEN-BRACE.

1,110,697.

Specification of Letters Patent. Patented Sept. 15, 1914.

Application filed August 2, 1913. Serial No. 782,630.

To all whom it may concern:

Be it known that I, MAX M. KOCH, citizen of the United States, residing at Cleveland, in the county of Cuyahoga and State of Ohio, have invented new and useful Improvements in Oven-Braces, of which the following is a specification.

My present invention pertains to braces for the top and bottom walls of the ovens 10 of steel-plate cooking ranges.

The said top and bottom walls in ranges of the kind stated are formed of sheet-steel; and one of the objects of my present invention is to provide a rigid brace for each wall, 15 the said brace being of open-work construction and extending throughout the area of the wall and being ribbed or arched and rigidly connected at frequent intervals to the wall in such manner as to absolutely 20 preclude warping of the wall, and this without interfering in appreciable measure with the heat conducting and radiating quality of the wall.

Another object of the invention is to so 25 construct the brace complementary to the bottom wall of the oven that said brace is adapted to hold and is also adapted for the strong connection of the flue strip usually employed in the flue below the bottom wall 30 of the oven.

Other advantageous characteristics of the invention will be fully understood from the following description and claims when the same are read in connection with the drawings, accompanying and forming part of this specification, in which:

Figure 1 is an inverted plan showing my novel brace as applied and connected to the underside of the top steel plate or wall of an 40 oven. Fig. 2 is a section taken in the plane indicated by the line 2—2 of Fig. 1, and showing the ribbed or arched character of some of the bars of the brace. Fig. 3 is a detail vertical section taken in the plane indicated by the line 3—3 of Fig. 4. Fig. 4 45 is an inverted plan showing the brace at the underside of the bottom wall or plate of the oven and also showing the flue strip properly applied and connected. Fig. 5 is a section taken in the plane indicated by the line 5—5 of Fig. 4 and showing the flue strip in side elevation.

Referring by numeral to the said drawings and more particularly to Figs. 1 and 2 thereof: 1 is the top steel plate or wall of the oven, bent downwardly as indicated by

2. Arranged against the underside of the top plate or wall is my novel open-work brace which is formed by preference of cast iron though it might be formed of any other material compatible with the purpose without affecting my claimed invention. The said brace is in one piece and comprises, by preference, side bars 3 forming a rectangle, cross bars 4 serving in connection with the side bars 3 to form smaller rectangles, open-work frames occupying the smaller rectangles and made up of connected diamond-shaped figures 5, and X-shaped figures 6 arranged at the outer sides of the side bars 3. 60 The several portions of the brace are ribbed or arched, as indicated by 7, with a view to increasing the stiffness and strength of the brace and enabling it to lend rigidity to the plate 1 and effectually prevent warping thereof. It will also be observed that at frequent intervals throughout its area, the brace is provided with apertures 8. These apertures are registered with countersunk apertures 9 in the plate 1 and are designed 65 for reception of connecting bolts 10, the heads of the bolts being disposed in the countersunk apertures of the plates while the nuts complementary to the bolts are arranged against the flat portions 11 of the brace. 70 At this point I would have it distinctly understood that while I prefer to fasten the brace close against the underside of the plate 1 through the medium of bolts and nuts, I do not desire to be understood as 75 confining myself to such specific mode of connection inasmuch as the brace may be riveted to the plate 1 without departure 80 from my claimed invention. At 12 the brace is provided with depending apertured 85 end portions, and these are bolted or otherwise fixedly connected to the downwardly bent portions of the plate 1. This is advantageous inasmuch as it enables the brace to hold the said downwardly bent portions 90 and tie the same to the horizontal major portion of the plate, and also because it enables the brace to hold the major portion of the plate down. It will further be observed 95 that at its forward end the brace is adapted 100 as indicated by 13 for its proper fastening in connection with the front oven door plate (not shown) of a range. 105

It will be gathered from the foregoing that my novel brace applied and connected 110 in the manner described is calculated to effectually prevent warping of the top plate

or wall 1 of a range oven and prolong the usefulness of the oven and range as a whole, and this without interfering with the passage of heat through the plate or wall; and it will also be gathered that the brace is inexpensive and is therefore not likely to materially increase the cost of a range.

In Figs. 3 to 5, 1^a is the bottom wall or plate of an oven; and it is to be understood that when said wall or plate is incorporated in a range it is disposed above and spaced from the bottom wall of the range, thereby forming a flue below the oven. It is also to be understood that 14 and 15 are the front and back downwardly bent portions of the plate or wall; 16, the upwardly bent portion of the plate or wall adjacent the uptake flue of a range; and 17, the downwardly bent portion of the plate or wall adjacent the fire box of the range.

The brace shown in Figs. 3 to 5 is generally similar in construction to the brace shown in Figs. 1 and 2 and is applied and connected in similar manner to the underside of the oven bottom plate or wall 1^a. It will also be noted that the brace of Figs. 3 to 5 has depending portions 21 bolted or otherwise connected to the downwardly bent portions 14, 15 and 17 of plate 1^a; and that said brace also has upwardly directed portions 22 bolted or otherwise connected to the upwardly bent portion 16 of the plate or wall 1^a.

The brace shown in Figs. 3 to 5 further differs from that shown in Figs. 1 to 3 in the respect that it is provided in the back portion of one of its cross bars with a groove or channel 23. The said groove or channel 23 is to receive and hold the upper edge of a flue strip 24 which is connected at 25 to the plate or wall 1^a and its complementary brace.

It will be readily noted from the foregoing that the brace shown in Figs. 3 to 5 is adapted to serve the same purpose with respect to the plate or wall 1^a that the brace

shown in Figs. 1 and 2 serves in combination with the wall or plate 1; also, that the brace shown in Figs. 3 to 5 is possessed of all of the practical advantages ascribed to the brace of Figs. 1 and 2.

Having described my invention, what I claim and desire to secure by Letters-Patent, is:

1. The combination of a sheet-metal oven plate having bent portions, and a rigid brace arranged against the plate and having bars arranged at angles to each other and spaces between the bars, and also having downwardly arched ribs on the bars and angularly disposed end portions on the bars, arranged against and connected to the bent portions of the oven plate; the arched ribs on the bars being spaced apart and the portions of the bars between the ribs being connected to the oven plate at intervals throughout the area thereof.

2. The combination of a sheet-metal oven plate having bent portions, a rigid brace arranged against the plate and having bars arranged at angles to each other and spaces between the bars and also having downwardly arched ribs on the bars, and angularly disposed end portions on the bars, arranged against and connected to the bent portions of the oven plate, and further having a channeled portion; the arched ribs on the bars being spaced apart and the portions of the bars between the ribs being connected to the oven plate at intervals throughout the area thereof; a flue strip the edge of which is disposed in said channeled portion, and means connecting said strip with the oven plate and the brace.

In testimony whereof I have hereunto set my hand in presence of two subscribing witnesses.

MAX M. KOCH.
